(57) **CLAIM**

The ornamental design for a surgical safety marker, as shown and described.

DESCRIPTION

FIG. 1 is an isometric view of a first embodiment of the surgical safety marker of the present invention;

FIG. 2 is a top plan view thereof;

FIG. 3 is a rear side elevation view thereof, the front side being a mirror image;

FIG. 4 is a right side elevation view thereof, the left side being a mirror image; and,

FIG. 5 is a top plan view of a second embodiment of the present invention, which is lined for color, the bottom and sides of which are identical to the first embodiment. The bottom is flat and otherwise unornamented.
